UNITED STATES PATENT OFFICE.

ALPHONSE H. KURSHEEDT, OF NEW YORK, N. Y.

SPANGLED FABRIC.

SPECIFICATION forming part of Letters Patent No. 631,310, dated August 22, 1898.

Application filed May 21, 1898. Serial No. 681,292. (Specimens.)

To all whom it may concern:

Be it known that I, ALPHONSE H. KURSHEEDT, residing in the borough of Manhattan, city, county, and State of New York, have 5 invented certain new and useful Improvements in Spangled Fabric, of which the following is a specification.

My invention relates to spangled fabrics, and has for its object to produce a spangled 10 fabric of such a character that it may be rapidly produced with the aid of machinery, the spangles being secured in place upon the fabric by a sewing mechanism or mechanism in the nature of a sewing machine.

15 My invention will be understood by referring to the accompanying drawings, in which—

Figure 1 is a plan view of a spangled fabric embodying my invention, the same being 20 shown upon a very large scale in order to clearly exhibit the structure thereof. Fig. 2 is a section on line 2 2 of Fig. 1.

In the drawings, which show one form of my invention, 1 is a fabric bearing the spangles 25 a b c d e. These spangles are held in place upon the fabric by a thread n and a thread s. In the present instance the thread n will be called the "needle-thread" and the thread s the "shuttle-thread." These threads are 30 shown in the present instance as running as follows: The needle-thread n passes downward through the fabric in a loop n', through which loop the shuttle-thread s passes in a loop s'. Thence the needle-thread ascends, passing 35 through the eye a' of the spangle a, thence across its upper face to its edge a'', thence downward through the fabric 1 in a loop n'', through which the shuttle-thread s passes in a loop s'', thence upward through the eye b' in 40 the spangle b, thence across the face of the spangle b to its edge b'', where it descends through the fabric in a loop n'', through which

the shuttle-thread s passes in a loop s'', and so on, repeating these courses. It will be obvious that this construction illustrated may 45 be more or less varied without departing from the spirit of my invention. It will be observed that the spangles are "strung" upon the thread n—that is to say, the thread passes through the eyes of the spangles in a continuous 50 course instead of passing therethrough in a loop. Consequently the thread crosses only half of the exposed face of the spangle instead of crossing them from edge to edge.

What I claim, and desire to secure by Letters Patent, is—

1. As a new and useful article of manufacture, a structure of the character described, to wit, a fabric 1, a series of spangles laid flatwise and means for securing the said spangles 60 to the said fabric, comprising a plurality of threads, one of the said threads passing through the spangles in series and another thread s interlocking with the said first-mentioned thread at points in the length of the 65 said thread between the points in the length of said thread where it passes through adjacent spangles, substantially as and for the purposes set forth.

2. As a new and useful article of manufacture, a structure of the character described, to wit, a fabric, a thread, a series of spangles 70 strung on the said thread and carried flatwise on the fabric, the said thread extending into the fabric in loops and secured to the fabric 75 at intervals by a thread on the opposite side of said fabric extending through the loops of the first-mentioned thread to interlock therewith.

ALPHONSE H. KURSHEEDT.
